CLARENCE C. WILSON, OF CORCORAN, CALIFORNIA.

PROCESS OF AND APPARATUS FOR PUMPING LIQUID AND GAS.

1,380,695.

Specification of Letters Patent. Patented June 7, 1921.

Application filed August 18, 1919. Serial No. 318,210.

To all whom it may concern:

Be it known that I, CLARENCE C. WILSON, a citizen of the United States, residing at Corcoran, in the county of Kings and State of California, have invented new and useful Improvements in Processes of and Apparatus for Pumping Liquid and Gas, of which the following is a specification.

The present invention relates to a method 10 of pumping water or other liquid when mixed with gas and to an improved apparatus for carrying out said method.

In the accompanying drawing, the figure 15 is a side view, certain parts being shown in section, of my improved apparatus.

There are districts in the State of California, as, for instance, in Kings county, where it is practically impossible to irrigate, although water for irrigation is found beneath 20 the surface of the soil at a depth of less than thirty feet, for the reason that the water is to such an extent mixed with gas, particularly with combustible gas, supposed to be derived from the decomposition of tules, 25 that it is not possible to draw the water to the surface of the ground by ordinary irrigation pumping methods. It is not possible to use an ordinary centrifugal pump for pumping the water out of the ground for 30 the reason that the gas, commingled with the water, collects in the pump until it breaks the "priming" of the suction pipe.

I have discovered that this difficulty can be overcome by providing two conditions in 35 conjunction with the centrifugal pump. The first condition is to place a foot valve in the suction pipe of the pump. The second condition is to provide a sufficient amount of water in the outflow pipe of the 40 pump capable of running back into the pump, when the pumping ceases temporarily, and ejecting the gas from the pump. I have used a third condition in actual practice, although I am not sure that this is a 45 necessary condition, namely, that the pump casing should be provided with a conduit or passage leading from the upper portion of the pump casing upwardly to permit the collected gas to escape.

50 Referring to the drawing, 1 indicates a centrifugal pump, 2 the outlet pipe therefrom leading upwardly to a tank 3 sufficiently large to hold a sufficient supply of water, capable of running back to the pump, 55 when the pumping ceases temporarily, to displace the gas collected therein. 4 indi-

cates a suction pipe of the pump leading from below the level of the water, and provided, below said level, with a non-return foot valve 5. 6 indicates an escape passage 60 for the gas collected in the pump casing, and leading into the outlet pipe 2.

Many attempts have been made to use centrifugal pumps for pumping in certain districts in California in which there is 65 water sufficiently near the surface of the soil and which water contains a considerable quantity of gas commingled therewith. But all such attempts have proved failures, for the reason that, after pumping a short 70 time, the gas pumped up with the water collects in the centrifugal pump casing, probably in the central portion thereof, until the priming of the pump is broken, and the water falls back down the suction pipe to 75 the level of the water in the well, which has to be primed over again before pumping can be renewed. The time and trouble of repeated reprimings required after pumping for a short time have caused such pumps to 80 be abandoned in these localities.

I have discovered that this difficulty may be overcome, first, by providing the foot valve 5 at the bottom of the suction pipe 4, thus preventing the dropping down of the water 85 to the level of the well; and, second, by providing means, as the tank 3 and the outlet pipe 2, for retaining a sufficient amount of water ready to flow back into the pump as soon as the pumping ceases; the object of 90 this supply of water being to expel the gas which collects in the pump, and enters the top of the suction pipe 4, thus breaking the priming. I also in practice employ a pump in which there is a passage 6 leading from 95 the upper portion to the outlet pipe 3 for the escape of gas so driven out by the descending water. However, said escape passage may be at a much lower level than as here indicated.

100 With such a construction, and provided that the pump proper is maintained in action, the pumping of the water or other liquid is automatically restored almost immediately after it has been cut off by the collection of gas in the pump chamber.

The pumping proceeds in the following manner:

110 The water and gas are drawn up through the suction pipe into the pump casing and the gas, being the lighter of the two, collects probably in the middle of the pump

casing, until it has collected to such an extent that the priming is broken and the centrifugal pump no longer acts to draw water from the suction pipe, and, therefore, no longer acts to force water into the outlet pipe. Water being no longer driven into the outlet pipe, the water already in the said pipe and the water in the tank flow back into the centrifugal pump, and displace the air therein, which escapes by way of the passage 6. The priming being now again completed, the pumping again starts automatically and proceeds as before until a sufficient quantity of gas is collected in the pump casing to break the priming, when

the pumping stops and water flows back again from the outlet pipe and tank and displaces the gas and restores the priming, and so on indefinitely.

I claim:—

The combination of a centrifugal pump, a suction pipe leading to said pump, a non-return valve in said pipe, an outlet pipe from the pump, a tank in free communication with said pipe and of sufficient size to hold the contents of the pump, and a passage leading from the upper portion of the pump to the outlet pipe.

CLARENCE C. WILSON.
